PRESSING IRON

Ivar Jepson, Oak Park, Ill., assignor to Sunbeam Corporation, Chicago, Ill., a corporation of Illinois

Application November 12, 1954, Serial No. 468,454

19 Claims. (Cl. 38—77)

The present invention relates to pressing irons and, more particularly, to a pressing iron capable of readily being converted to a steam iron so that it may serve equally well as a steam or dry iron. Specifically, the present invention is an improvement on prior copending application Serial No. 192,671 filed October 28, 1950, now Patent 2,744,344, and assigned to the same assignee as the present application.

In the above mentioned copending Jepson application there is disclosed and claimed a pressing iron which may be converted to a steam iron by connecting a steam generating chamber defined in the iron to an external source of water. With this arrangement the electric iron does not need to include the conventional water tank for holding the water to be converted to steam and which water tank, of course, increases the size and the weight of the iron. It will be appreciated that pressing irons of the type convertible to steam irons wherein the source of water to be converted to steam is an external source connected by a suitable conduit with the iron can comprise a much smaller and more compact unit as far as the iron itself is concerned and more satisfactory to the housewife who has to manipulate the iron than steam irons which have a built-in water tank. Steam irons of the type having a built-in water tank must be relatively light since housewives just refuse to push around heavy irons after having experienced extensive use with light-weight irons. This means that the built-in water tank must be relatively small, since otherwise it will be a factor in increasing the weight of the iron when the tank is full and if the tank is large will be clumsy and unsightly. A small built-in tank has the disadvantage, however, that it requires repeated refilling by the housewife. This, in itself, would not be a serious problem if the housewife could merely place the iron under the faucet and add additional water to the built-in tank. Unfortunately in a great many localities ordinary tap water contains various amounts of mineral impurities which upon converting such water to steam are deposited within the iron, and particularly within the water flow control orifices and the steam ports, employed in such irons.

In steam irons of the so-called flash boiler type which have proven to be by far the most satisfactory type of steam iron, there are included small orifices and passageways controlled by needle valves which gradually fill up with mineral impurities if tap water is employed. As a matter of fact in many localities where the water is generally referred to as "very hard" these passageways and orifices are affected adversely so as to render the iron unfit with use after a very short time, such as one or two uses of the iron. As a result of this manufacturers who are completely honest with their product make it clear to the public that their steam iron should be used only with distilled water. This means that the housewife must purchase the distilled water and transfer the distilled water from the container in which it was purchased to the reservoir of the steam iron. With the conventional steam iron holding only about five ounces of water, it can

2

readily be appreciated that extensive filling of the built-in tank of the steam iron is necessary during an ironing operation if it is intended for the iron to produce real quantities of steam, which is important for satisfactory steam ironing. Housewives have objected to this repeated filling of the iron with distilled water, and many have resorted to using tap water with the result that the iron soon fails to work and the manufacturer gets complaints that his steam iron is unsatisfactory.

10 In a pressing iron of the type disclosed in the above-mentioned copending application, this problem is completely obviated by having the housewife leave the distilled water in the container in which it was purchased or pouring it into another container which is very large and which may contain sufficient water for doing a complete ironing or several ironings without refilling. This type of steam iron has a tremendous advantage in that there is never more than a drop or two of water in the iron itself and, hence, the weight of the iron is the same 15 whether used as a steam iron or as a dry iron and may be very light. It would be desirable to provide a steam iron of the type disclosed in the above-mentioned copending application which provides a greater ironing surface, a larger steam generating chamber and which is furthermore more capable of use for ironing pockets, sleeves, and the like in that it can get into those hard-to-get-at places. At the same time it would be desirable 20 to provide an iron that is small and compact, having a low overall height and yet which has all the desirable features and control of the steam iron of the copending application which has proven to be commercially very successful.

Accordingly it is an object of the present invention to provide a new and improved pressing iron which may 25 readily be converted from a dry iron to a steam iron or vice versa and which has the same weight whether used as a steam iron or as a dry iron.

It is another object of the present invention to provide a new and improved pressing iron readily convertible 30 to a steam iron which can be used to iron pleats, ruffles, sleeves and the like with greater ease than irons heretofore available.

It is another object of the present invention to provide a new and improved pressing iron with simple and compact means for selectively controlling the temperature 35 thereof for different ironing operations.

It is a further object of the present invention to provide a pressing iron of the "open handle" type with control means for controlling one of the variable characteristics 40 of the iron by means of a knob on the end of the handle.

It is another object of the present invention to provide a new and improved steam iron in which a constant flow of water is provided at all times under a sufficient pressure-head to insure the production of large quantities of steam which will cause deep steam penetration of the 45 goods being ironed.

It is another object of the present invention to provide a new and improved steam iron employing only distilled water which will not require periodic filling of a water tank and emptying of the tank when the ironing operation is completed, but which may be used for many hours 50 without filling and which is simple, compact and very sturdy in construction.

It is another object of the present invention to provide 55 a steam iron of the flash-boiler type having an improved steam generating chamber.

A still further object of the present invention resides in the provision of a new and improved steam iron which is substantially instantaneous in operation providing the steam within approximately thirty seconds after the iron 60 is plugged in.

Further objects and advantages of the present invention

tion will become apparent as the following description proceeds and the features of novelty which characterize the invention will be pointed out with particularity in the claims annexed to and forming a part of this specification.

For a better understanding of the present invention reference may be had to the accompanying drawings in which:

Fig. 1 is a perspective view of a portion of an ironing board with which is associated the pressing iron of the present invention connected for operation as a steam iron;

Fig. 2 is a perspective view of the pressing iron only of the present invention showing only a portion of the electrical and water connections thereto;

Fig. 3 is a longitudinal sectional view taken substantially along line 3—3 of Fig. 2 and showing the control switch in the off position;

Fig. 4 is a sectional view taken on line 4—4 of Fig. 3 assuming that Fig. 3 shows the complete structure;

Fig. 5 is a greatly enlarged sectional view taken on line 5—5 of Fig. 4, again assuming that Fig. 4 shows the complete structure;

Fig. 6 is a greatly enlarged view with certain portions cut away of the temperature responsive control means employed in the pressing iron of the present invention but shown with the switch contacts of the control means shown in the closed position;

Fig. 7 is an enlarged top-plan view of the pressing iron of Fig. 2 with certain portions broken away better to illustrate the steam generating chamber and the like;

Fig. 8 is a greatly enlarged sectional view taken on line 8—8 of Fig. 7 assuming that Fig. 7 shows the complete structure;

Fig. 9 is a longitudinal sectional view of the cover of the steam generating chamber showing the position it assumes before attachment to the steam generating chamber;

Fig. 10 is a sectional view taken on line 10—10 of Fig. 9;

Fig. 11 is a greatly enlarged fragmentary sectional view taken on line 11—11 of Fig. 9;

Fig. 12 is a fragmentary bottom view of the sole plate of the pressing iron of the present invention to illustrate the steam ports and the steam distributing grooves provided therein; and

Fig. 13 is a somewhat schematic circuit diagram of the electrical circuit of the pressing iron of the present invention with the control switch shown in the closed position or in other words, the energized position of the iron.

The pressing iron of the present invention comprises an open handle iron with a sole plate having the well-known U-shaped form of heating element embedded therein and with a very large steam generating chamber defined over a substantial portion of the sole plate area confined within the confines of the U-shaped heating element. The steam generating chamber has ports leading therefrom to the bottom surface of the sole plate while a conduit connected to an external source of water terminating in a fixture on the outside of the iron connects this fixture with the steam generating chamber so that when connected to an external source of water, water will be supplied to the steam generating chamber for conversion to steam. In view of the open handle construction novel and yet very effective means for controlling the temperature setting of the iron are provided including a control knob mounted at the end of the iron handle. A very compact construction is provided.

Referring now to the drawings there is illustrated the pressing iron 20 of the present invention having the conventional power cord 21 which may be connected to any suitable wall outlet as will readily be understood by those skilled in the art. The iron 20 as viewed in Fig. 1 is illustrated as being associated with an ironing board 22 which of course forms no part of the present invention.

tion. In order that the pressing iron 20 may be readily converted to a steam iron there is provided an attachment generally designated by the reference numeral 25 in Fig. 1 of the drawings. This attachment 25 generally comprises a water tank and conduit means for connecting the tank to the iron 20 and controlling the water flow thereto. Specifically it comprises a support 26 which is designed to be clamped to the edge of the ironing board preferably at one end of the board as illustrated in Fig. 1. The support 26 is designed to position a container 27 a predetermined distance, such as eighteen inches or the like, above the surface of the ironing board 22. This container 27 which may have a removable cover 28 is connected by means of a flexible tubular member or conduit 29 to the pressing iron 20. The flexible conduit 29 is in turn connected to a rigid conduit 30 which rigid conduit is adapted to be connected with the pressing iron 20. Actually the flexible tube 29 and the rigid conduit 30 may be identical with that disclosed and claimed in the above-mentioned copending application.

Preferably the end of the rigid conduit 30 adjacent the flexible tube 29 as is best shown in Fig. 2 of the drawings is provided with a molded unit 31 which comprises a shut-off valve and a cord support. The shut-off valve includes a manually operable knob 32 which can be moved to either the "On" or the "Off" position as indicated in Fig. 2, it being shown there in the "Off" position. The molded member 31 includes a clip portion 31a to receive therein the power cord 21 whereby the flexible conduit 29 and power cord 21 tend to be held together adjacent the iron. It will also be apparent that the rigid conduit 30 will then hold not only the end of the flexible tube 29 but also the power cord 31 in a predetermined relationship relative to the iron to make it very easy for the housewife to manipulate the iron without interference from either the power cord or the flexible conduit 29. It has been found in connection with the steam iron disclosed and claimed in the above-mentioned application that housewives actually prefer to keep the rigid conduit 30 in position when the iron is not being used as a steam iron since it maintains the power cord 21 out of the way. Under these conditions the flexible conduit 29 may be disconnected from the molded unit 31 which preferably has a nipple extending therefrom for insertion into the flexible conduit 29.

It should be understood that the container 27 will be one holding a substantial quantity of water and the housewife will fill it with distilled water and can then iron for many, many hours and over a period of several days without refilling as contrasted with the conventional tank-type steam irons where repeated filling of a relatively small tank is required. Preferably, and as indicated in Fig. 1 of the drawings, the tank 27 is provided with some sort of a strainer designated at 35 to prevent any foreign matter from getting into the flexible conduit 29. It will be understood that by virtue of the fact that the container 27 is mounted a predetermined distance above the ironing board 22 it will provide a constant pressure-head of water. If desired the distilled water may be used directly from the container in which it is purchased and a suitable pump arrangement for applying pressure thereto may be provided. Such an arrangement is disclosed in the above-mentioned copending application and it will be appreciated that that arrangement may be employed equally well instead of the gravity arrangement disclosed in Fig. 1 of the drawings.

Preferably the flexible conduit 29 is formed of rubber or plastic material and is designed relative to the pressure-head of the source to feed to the pressing iron at least 0.35 ounce of water per minute. The internal diameter of the flexible tube may be of the order of .065 inch and with the pressure-head provided by having the tank 27 disposed eighteen inches above the ironing surface, the desired flow of at least 0.35 ounce per minute is obtained. This diameter is many times the diameter of ori-

fices employed in conventional steam irons and the area of the passageway is therefore between ten and twenty times greater than the area of the orifices of prior steam irons. As a result of this, the resistance to water flow with the steam iron of the present invention is primarily that provided by the flexible conduit 29 and since this resistance to flow is relatively large under all circumstances there is a relatively small change in impedance to flow when ironing dense as against less dense goods so that much deeper and better steam penetration is obtained with the pressing iron of the present invention than with conventional steam irons having a built-in water tank. In this regard the pressing iron of the present invention has the advantages set forth in the above-mentioned copending application.

Considering now the details of the pressing iron of the present invention, reference may be had particularly to Figs. 3 to 11 of the drawings. The iron is in many respects similar to that disclosed in the above-mentioned copending application. As illustrated the pressing iron 20 comprises a sole plate 40 heated by an electrical heating element 41 which preferably is of the sheathed type. Such types of heating element are well known and generally comprise a helical resistance conductor centrally disposed within an outer metallic sheath. Supported in spaced relationship with reference to a sheath is an insulating heat-conducting mass formed of a suitable material such as highly compressed magnesium oxide. This latter material has been found to provide the desired insulation and at the same time have sufficiently good heat conducting properties so as not to delay the transfer of heat from the coiled resistor element disposed centrally of the sheath to the sheath and hence to the sole plate which it is desired to heat. The sheathed heating element 41 is best shown in Figs. 3, 4 and 7 of the drawings and has a generally U-shaped configuration or roughly in the shape of a hairpin with the extremity of its legs designated as 41a and 41b respectively disposed at the rear of the iron and its bight portion 41c disposed at the front or pointed end of the sole plate 40. Preferably the U-shaped heating element 41 is embedded in the sole plate 40 as by being cast therein during the process of casting the sole plate from suitable materials such as aluminum or the like. As illustrated in the drawings and specifically in Fig. 7 thereof, the sole plate is provided with an integral upwardly extending U-shaped rib 40a in which the sheathed heating element 41 is received. The sheathed heating element 41 is moreover provided with suitable terminals 43a and 43b extending out of the metallic sheath as best shown in Figs. 4 and 7 of the drawings, it being understood that these terminals are suitably connected to the centrally disposed resistance element.

For the purpose of defining a steam generating chamber which is in good heat transfer relationship with the heating element 41 or at least with the rib 40a in which the heating element 41 is disposed, the front upper portion of the sole plate 40 is provided with a well or chamber generally designated as 45 which may be referred to as the steam generating chamber. This steam generating chamber 45 is defined within the space bounded by the closed end of the U-shaped rib 40a and a cross-member 46 (Figs. 3 and 7) which extends between the two legs of the U-shaped rib 40a and effectively interconnects these legs. This cross-member 46 is disposed a substantial distance away from the bight of the U-shaped rib 40a so that a very large steam generating chamber is provided, taking up more than half of the surface area of the sole plate between the legs of the U-shaped heating element 41.

In order that a satisfactory steam generating chamber may be defined which is closed to atmosphere except for the steam exit passageway and the water inlet passageway the adjacent top edge of the rib 40a enclosing the steam generating chamber 45 is provided with a flat ledge or sealing surface generally designated as 47 which is level with the top of the cross-member 46 for supporting thereon a suitable cover or closure 48 for the steam gen-

erating chamber 45. The cover 48 of the steam generating chamber 45 forms an important feature of the present invention.

Heretofore it has been common practice to employ some sort of gasket or sealing cement between cover such as 48 of the steam generating chamber and the sealing ledge 47. In accordance with the present invention and as best shown in Figs. 7 to 11 of the drawings the cover 48 is effectively a three-part cover comprising an upper stainless steel member 48a, an intermediate asbestos member 48b and a lowermost aluminum foil member 48c. In a commercial embodiment of the present invention the stainless steel cover plate 48a had a thickness of $\frac{1}{16}$ of an inch, the asbestos layer 48b had a thickness of $\frac{1}{32}$ of an inch and the aluminum foil 48c had a thickness of 0.004 of an inch. All three of these members forming the cover 48, have the configuration shown in Fig. 7, conforming with the shape of the ledge or sealing surface 47. Also in accordance with the present invention the stainless steel cover element 48a is initially bowed as shown in Figs. 9 and 10 of the drawings, so that when drawn into sealing engagement by suitable fastening means with the ledge 47 the cover will be stressed to provide a good seal all around the edge. It will be appreciated that the asbestos layer 48b affords the necessary resilience for a good seal and the aluminum foil 48c keeps the water and steam from the steam generating chamber 45 from coming in contact with the asbestos layer 48b. In addition the aluminum foil provides a metal to metal seal with the ledge 47 and the aluminum conforms to any unevenness of the ledge 47. The stainless steel layer 48a in effect provides a backing plate to uniformly transmit the sealing force to the entire periphery of the cover 48.

For the purpose of holding the three layers 48a, 48b and 48c as a sort of sub-assembly use is made of the conduit for supplying water to the steam generating chamber 45. To this end there is provided a short length of conduit 49 preferably of copper or the like and having a diameter comparable with that of the flexible tubing 29 discussed above. This conduit 49 the major portion of which extends generally in the longitudinal direction of the sole plate as is apparent from Fig. 7 has the end adjacent the steam chamber 45 bent at right angles so as to extend generally downwardly and this downwardly directed portion extends through aligned openings in the layers 48a, 48b and 48c. A suitable washer 50 is slipped over the end of the tube extending through the three layers as best shown in Fig. 8 of the drawings and the end of the tube is peened over as indicated at 49a, thereby to secure together the three layers forming the cover 48 so that these three layers together with the conduit 49 form a subassembly. The other end of the conduit 49 is bent at an angle as indicated at 49b and terminates in a bushing 52 by means of which external connection with the external water source described above can be made as will become apparent from the following description.

To secure the cover 48 to the steam chamber 45 in sealing relationship with the sealing surface 47 there are provided a plurality of screws or fastening means 53, five being shown in Fig. 7 of the drawings and specifically designated as 53a, 53b, 53c, 53d and 53e. These screws extend through the cover 48 and are secured in tapped openings defined in the sole plate 40. As illustrated three screws 53a, 53b and 53c are used along the portion of the cover 48 disposed toward the rear of the iron 20 and are effectively secured to the cross-member 46 or integral extensions thereof. The screw 53d engages a tapped opening pretty much centrally disposed of the steam generating chamber 45, so that by tightening the screw 53d the bowed configuration of the cover 48 is distorted so as to provide a very good seal all along the sealing edge 47 around the steam generating chamber 45. The screw 53e extends through the front central portion of the cover 48.

In order to be sure that only dry steam reaches the

pressing surface of the iron the water supplied to the steam generating chamber through the conduit 49 enters the chamber adjacent the rearmost portion thereof, as is best shown by Figs. 7 and 8 of the drawings. Moreover, a suitable raised portion 54 in the form of a cylindrical protuberance is provided within the steam generating chamber 45 immediately beneath the opening of the conduit 49. Thus the water supplied to the steam generating chamber through the conduit 49 drops onto the raised protuberance 54. This water must move the entire length of the steam generating chamber to reach steam outlets which comprise ports 56 located at the extreme forward portion of the steam generating chamber 45. Furthermore, these ports are in the bottom of a relatively deep cylindrical recess 57 obviously also disposed at the extreme forward end of the steam generating chamber. It will be apparent that since recess 57 is confined within the bight of the U-shaped heating element 41 that it is located at the hottest portion of the sole plate.

To obtain distribution of the steam at the ironing surface over a substantial area of this ironing surface, the pressing surface of the sole plate 40 may be provided with a plurality of elongated grooves or notches designated at 58 and best shown in Figs. 3 and 12 of the drawings. These notches may have any configuration but are illustrated as providing a Y-shaped configuration with the common portion of the Y adjacent the ports 56 and in fact, each groove having one of these ports 56 terminating therein. These grooves 58 will, with the goods being ironed, define steam passageways to distribute this steam over a substantial area of the sole plate.

From the above description it will be apparent that water enters the large steam generating chamber 45 near the rear corner thereof and steam leaves the steam generating chamber near the forwardmost point thereof. To insure conversion of this water to dry steam while it is moving from the back of the steam generating chamber 45 to the front thereof, means are provided to make the available passages very tortuous. To this end there are provided a plurality of transverse barriers 60, 61, 62 and 63 which are integral with the sole plate 40 and extend upwardly from the bottom of the steam generating chamber into engagement with the cover 48. The ends of these transverse barriers do not quite extend to the side walls of the steam generating chamber 45. As illustrated in Fig. 7 of the drawings the barriers 61 and 63 are provided with enlargements to receive the screws 53d and 53e for securing the cover 48 to the sole plate 40. Interposed between these transverse barriers 60, 61, 62 and 63 are a plurality of transverse barriers 64, 65, 66, 67, 68, 69, 70 and 71. The barriers 64 and 65 extend towards each other from the sides of the steam generating chamber between the barriers 60 and 61 but do not quite join in the center, thus providing a steam passageway therebetween. Similarly the barriers 66 and 67 project from the side walls between the barriers 61 and 62 and again do not quite join in the center. Similarly the barriers 68 and 69 extend between the barriers 62 and 63 leaving a passageway at the center of the iron. All of these barriers integral with the sole plate extend to the level of the sealing surface 47 so that sealing engagement with all of these barriers and the cover 48 is made. The barriers 70 and 71 are similar to the others extending in from the side walls and are between the barrier 63 and the recess 57. Thus water entering the steam generating chamber 45 by dropping on the raised protuberance 54, to reach the recess 57 and hence the outlet ports 56 must take one of several very tortuous paths as is clear from the arrows in Fig. 7 from the drawings. For the purpose of further insuring that only dry steam reaches the ports 56 there may also be inserted within the steam generating chamber 45 a suitable metal mesh or wool. Two such pieces of metal mesh which may be formed of a non-corrodible metal such as Monel metal or the like are designated by the reference numeral

72. As illustrated in Fig. 7, the metal wool pieces are indicated as being of somewhat U-shaped form around the ends of the barriers 62 between the barriers 66 and 68 in one case and the barriers 67 and 69 in the other case. By the time the water supplied to the steam generating chamber reaches the recess 57 it has of course been converted to superheated steam. Moreover, to get into the recess 57 it is necessary for the steam to go through a narrow passageway between barriers 70 and 71 and over a relatively high wall surrounding recess 57. Thereby all water droplets not converted to steam must remain to the rear of the wall section defining the recess 57. It will furthermore be apparent that the recess 57 which is enveloped on three sides by the U-shaped heating element tends to be disposed in the hottest portion of the iron, thus insuring super-heated steam.

For the purpose of making sure that the water drops supplied to the steam generating chamber 45 will wet the bottom surface of the steam generating chamber 45 and the side walls thereof, the entire interior of the steam generating chamber is coated with a suitable wetting agent.

A suitable wetting agent for this purpose is disclosed in the above mentioned co-pending Jepson application.

25 It is found that when the steam generating chamber is coated with a suitable wetting agent a sufficient temperature drop at the surface of the steam generating chamber walls is provided, which results in the water wetting the surface and providing the desired generation 30 of steam. Numerous coatings may be employed which will operate satisfactorily for a time, but many of these will wash away as distilled water continually is supplied thereto.

It will be apparent that the provision of the steam generating chamber 45 and the conduit for supplying water thereto together with the ports 56 and associated grooves 58 in the sole plate ironing surface are necessary to make a steam iron of the pressing iron 20. However, all other features thereof are those essential whether the iron is used 40 as a steam or a dry iron. It will be apparent that the upper surface of the sole plate including the cover of the steam generating chamber and the conduit 49 supplying water thereto as well as the raised rib 40a of the sole plate 40 are not very attractive in appearance, and to complete the pressing iron of the present invention there is preferably provided a suitable sole plate cover 73. This cover is of somewhat inverted dish shape having a configuration in some respects very similar to the shape of the sole plate 40 but extending some distance beyond the rear thereof. This cover or shell 73 has a peripheral flange 73a which engages with the top of the sole plate along the top edge thereof. Preferably the sole plate 40 is provided with a ledge 40b all around the top periphery thereof except across the rear of the iron for engagement 55 with the peripheral depending portion 73a of the shell or cover 73.

In order to secure the shell or cover 73 to the sole plate 40 there is provided on the upper surface of the sole plate a pair of upwardly extending bosses 40c and 40d. These 60 bosses are formed integrally with the sole plate just to the rear of the steam generating chamber 45 and are provided with tapped openings to receive certain suitable fastening screws 74. In this way the cover or shell 73 is rigidly secured to the sole plate and becomes a unit therewith.

The portion of the shell or cover 73 extending beyond the heel of the sole plate 40 provides a housing affording access to suitable fastening means for securing a handle to the sole plate and the like. In order to enclose this 70 housing section to the rear of the sole plate 40, there is provided a suitable closure plate 75 which is adapted to engage certain projections 40e formed integrally with the sole plate. A suitable screw 76 engaging with a stud 77 secured to the shell 73 holds the plate 75 in place. 75 Preferably a portion of reduced cross-section of the stud

77 is inserted into an opening in the shell 73 and the end of this reduced cross-section is peened over to thereby secure the stud 77 to the shell 73. This provides a simple means for securing the closure plate 75 in position.

In order that a major portion of the sole plate 40 can be inserted into the ends of sleeves, deep ruffles, and the like, without interference from the handle, as was the case with prior pressing irons, there is provided a handle generally designated as 80 which is of somewhat L-shaped configuration comprising a hollow hand grip portion 80a disposed somewhat in a horizontal plane when the ironing surface of the sole plate is resting on an ironing board or the like, and a sort of post portion 80b which with the portion 80a defines a sort of L. The post portion 80b is also hollow and extends toward the sole plate 40 terminating in a somewhat enlarged sort of shell portion 80c adapted to overlie the shell 73.

In order that the handle 80 may be secured to the sole plate 40 or to the shell 73 which in turn is secured to the sole plate 40, there is provided a handle mounting plate 82. This handle mounting plate has a configuration substantially like that of the skirt portion 80c of the handle 80. The handle 80 is preferably formed of a molded insulating material such as one of the many synthetic resins capable of withstanding relatively high temperatures in the neighborhood of 275° to 300° F. During the molding operation of the handle there preferably are molded into the portion 80c a plurality of threaded metal inserts by means of which the handle plate 82 may be secured to the handle 80. As illustrated a plurality of screws 84 extend through openings defined in the handle plate 82 and engage the threaded inserts molded into the handle 80. The plate 82 is preferably provided with means to space it slightly from both the handle 80 and the cover or shell 73 thereby to reduce the heat transfer between these members.

With the handle plate 82 secured to the handle 80 there is provided a very simple means of securing the handle 80 to the shell 73 and hence to the sole plate 40. As illustrated the forward portion of the plate 82 is provided with depending hook members 82a which are adapted to be inserted in suitable openings 73b defined in the cover or shell 73 and hook the forward edges of these openings. Preferably raised protuberances 82b defined in the handle attaching plate 82 permit the same to rest on top of the screws or fastening means 74 which secure the cover 73 to the sole plate. To further secure the handle 80 to the sole plate a pair of screws 86 are inserted through openings near the rear of the shell 73 into suitable nuts which may be welded or otherwise secured to the handle attachment plate 82. These screws 86 can readily be inserted from the underside when the cover plate 75 is removed so that when the cover plate 75 is replaced, the fastening means are entirely concealed. The shell or cover plate 73, the handle plate 82, and the portion 80c of the handle 80 are provided with suitable somewhat aligned openings through which the bushing 52 connected to the water supply conduit 49 may extend. In order to provide means for readily connecting the conduit 49 with the external water supply and specifically with the rigid conduit 30 there is provided a sleeve 88 which threadedly engages the bushing 52 and is provided with an external thread 88a to accommodate ready connection with the external rigid conduit 30. This sleeve is preferably chrome plated so as to provide a very pleasing appearance and is substantially identical to the arrangement disclosed and claimed in the above-mentioned copending application. To prevent lint or foreign material from entering the sleeve 88 there is provided a suitable cap 90 pivotally mounted to suitable supporting means secured to the handle attaching plate 82. This cap tends to close the open end of the sleeve 88 when the iron is used as a dry iron. When the iron is used as a steam iron the cover 90 is pivoted about its hinged pivot to permit the insertion of

the rigid conduit 30 discussed above. The open position of this cover 90 is shown in Fig. 2 of the drawings.

With the arrangement described above and by virtue of the fact that the handle 80 is very low it will be apparent that there is little room for temperature control means which heretofore have been contained within wells defined within the sole plate. In accordance with the present invention the hollow handle 80 and specifically the post portion 80b is provided with a relatively large chamber 91 to at least partially accommodate a suitable temperature responsive control means generally indicated at 92 for selectively controlling the temperature of the sole plate 40. Any temperature responsive control device associated with the iron 20 should be one that will permit maintaining any selected accurate temperature of the ironing surface of the sole plate 40. The space for mounting the temperature control device 92 is behind the steam generating chamber 45. Since the water supplied through the conduit 49 is supplied to the steam generating chamber 45 adjacent the rear portion of the steam generating chamber, and since this water is at a relatively low temperature even though it has been warmed to some extent by traveling along the conduit 49 which is fairly close to the heating element 41, there is a likelihood of producing an area or zone adjacent the cross-member 46 not representative of the temperature of the sole plate. To make sure that the thermal-responsive device 92 is responsive to the average temperature of the sole plate there is provided a raised support 94 for the thermal-responsive device 92 which is integral with the sole plate 40 but which is separated from the cross-member 46 by a recess 93 thus effectively providing a heat barrier between cross-member 46 and support 94. This support 94 acts as a support for the thermal-responsive device 92 which can then be responsive to the temperature of this support 94 which is approximately that of the sole plate 40. The recess 93 between the elements 46 and 94 insures that the support 94 will not be adversely affected by the cooling effect produced by the water supplied to the steam generating chamber closely adjacent thereto.

The thermal-responsive control device 92 comprises a sub-assembly which is adapted to be secured as a unit to the support 94. One of the principal elements of the thermal-responsive control device 92 is a bimetallic element 96. This forms the bottom of the sub-assembly and is disposed so that when the sub-assembly is clamped to the support 94 the bimetallic element 96 is mounted in cantilever fashion with the fixed end thereof in good heat conducting relationship with the support 94 whereby the bimetallic element 96 is responsive to the temperature of the sole plate 40. As illustrated the high expansion side of the bimetallic element 96 is defined opposite the support 94 so that as the temperature of the sole plate rises the bimetallic element 96 will deflect downwardly.

The thermal-responsive control device 92 further includes a pair of spring contact arms 97 and 99 having supported at the free ends thereof switch contacts 98 and 100 respectively. These contacts 98 and 100 are designed to provide a switch for controlling the flow of current to the heating element 41. The contact arms 97 and 99 are suitably supported within the subassembly in insulated relationship. The contact 98 might be considered the moveable contact while the contact 100 might be considered the stationary contact, although the contact 100 is selectively moveable to provide the desired temperature control. The sub-assembly 92 also includes a connector device 103 for electrically connecting a thermal-responsive control device 92 with the terminal 43a of the heating element 41. Preferably there is welded to the terminal 43a an L-shaped conductor 104 which is connected to the connector 103 by a suitable fastening means 105. There is also included in the sub-assembly a connector 106 which is mounted in the stack of elements comprising the thermal-responsive element 92 which is connected to the

terminal 43b of the heating element 41 through another L-shaped conductor 107 and fastening means 108. The connector 106 includes an extension 106a defining a terminal which extends in a vertical direction into the chamber 91 defined within the post 80b of the handle 80 for connection to the power cord 21 as will be described hereinafter. Similarly there is another terminal 109 also extending into the chamber 91 within the post 80d for making electrical connection with the other conductor in the power cord 21 as best illustrated in Figs. 3 and 13. The elements 96, 97, 99, 103 and 106 are suitably assembled into a stack with interposed insulating members so that by completing the connections with the power cord to the terminals 106a and 109 and by completing the connections with the fastening means 105 and 108 the schematic circuit of Fig. 13 is completed whereby power may be supplied to the heating element 41 through the switch contacts 98 and 100 when these contacts are closed. The various elements 96, 97, 99, 103 and 106 are also suitably insulated from each other so that the illustrated circuit is provided and they are held together with each other and with a suitable cam support 110 by means of hollow rivets 111. These rivets are hollow so that suitable fastening means 112 may extend through the hollow rivets and secure the entire sub-assembly 92 to the sole plate and specifically to the raised portion 94 whereby the bimetallic element 96 is in good heat transfer relationship with the sole plate.

In order that the bimetallic element 96 may open the switch comprising the contacts 98 and 100 the end of the bimetallic element is bifurcated as indicated in Fig. 4 and the bifurcations 96a and 96b are interconnected by a suitable element welded to the bifurcations for supporting thereon an insulating crossbar 115. A suitable Z-shaped member 116 is secured to the contact arm 97 so that it extends between the bifurcations of the bimetal 96 and into the path of movement of the insulating member 115. Preferably the member 116 includes a compensating thermostat responsive to the ambient temperature of the iron. As the bimetal 96 deflects and the insulating crossbar 115 moves downwardly it engages the extension 116 and moves the relatively moveable contact 98 away from the contact 100.

It will be appreciated that different settings of the iron temperature are necessary for various operations. For example, when ironing synthetic materials such as rayon and the like an entirely different temperature is necessary than when ironing cotton or linen goods and also there are certain temperatures that are most desirable when operating the iron as a steam iron. Accordingly, means are provided for selectively changing the position of the stationary contact 100 whereby the operator may manually position this contact and thereby change the temperature at which the sole plate 49 is maintained. To this end there is provided an insulating cam 121 pivotally mounted to the cam support 110 as indicated at 122. A suitable spring 124 which has the central portion thereof wrapped around the pivot pin 122 and the ends 124a and 124b engaging the support 110 and the cam 121 respectively tends to rotate the cam 121 in a counter-clockwise direction as viewed in Figs. 3 and 6 of the drawings. The cam 121 is provided with a cam surface 121a which is adapted to engage a sort of a raised portion on switch-arm 99 thereby accurately to control the positioning of stationary contact 100.

Since as will become apparent from the following description the means for controlling the position of the cam 121 is a linear means, the cam surface 121a cannot comprise a linear cam surface since the operation of the bimetallic element 96 is not linear. It will be obvious that as the bimetallic element deflects further and further the bias of the forces against which it operates are increased since effectively the spring bias of the contact lever 97 opposes the bimetallic element as do also the

inherent forces in the bimetallic element itself. Moreover, at higher temperatures of the iron the heat losses are greater and thus a non-linear cam surface 121a is necessary. In a commercial embodiment built in accordance with the present invention the cam surface 120a comprised several sections each having a different rate of rise to provide the non-linear cam surface 121a. Preferably the cam 121 is made from a suitable insulating material such as a glass laminate with a silicone resin binder which can readily withstand the temperatures involved, and which can be constructed on a narrow strip and still provide a satisfactory cam surface.

In order that the operator may control the selective positioning of the stationary contact 100 in a simple and easy manner there is provided a manual control means in the form of a control knob 130 mounted for relative rotation with respect to the handle 80 at the end of the hand-grip portion 80a with the knob 130 effectively appearing as a continuation of the handle as clearly indicated in Figs. 2 and 3 of the drawing. For the purpose of rotatively supporting the knob 130 and suitable control means actuated thereby there is provided a rotatable shaft 131 which is mounted for rotation within a passage-way 132 defined substantially parallel with the longitudinal axis of the handle portion 80a. There is also defined within the chamber 91 in the post portion 80b of the handle 80 a depending section 80d which has an opening effectively to provide a bearing for one end of the rotatable shaft member 131. The other end of the rotatable shaft member 131 is suitably secured to the knob 130 in a manner to be described hereinafter. To provide an effective bearing for this end of the shaft 131, the knob 130 is provided with a portion 130a of somewhat reduced cross section which is capable of being inserted into a conforming recess 133 defined in the end of the handle portion 80a and effectively comprises a continuation of the chamber 132. Thus, a portion of the knob 130 is nested within the end of the handle 80a and when attached to the shaft 131 effectively provides a satisfactory bearing for that end of the shaft 131. The knob 130 is hollow to define a chamber 135 therein into which the end of the shaft 131 extends by passing through a portion of the knob 130. A suitable member 136 is secured to the shaft 131 and is clamped against one face of the knob 130 by means of a clamping nut 137 and an interposed washer 138. It will be appreciated that relative rotation for adjustment purposes can be obtained between the member 136 and, hence, the shaft 131 and the knob 130. To improve the appearance of the knob 130, the chamber 135 is preferably closed by closure member 140 held in place by a screw 141 engaging a stud 142 which is suitably secured to the end of the shaft 131.

For the purpose of transmitting rotatable movement of the knob 130 to pivotal movement of the cam 121, the end of the shaft 131 which extends into chamber 91 has secured thereto a suitable gear 144 which is adapted to drivingly engage a rack 145a forming a part of a reciprocally movable lever 145 pivotally secured as by a pivot pin 146 to the cam 121. The rotatable movement of the gear 144 will then cause pivotal movement of the cam 121 to provide any desired selected temperature. A suitable washer 148 and a nut 149 secured to the end of the shaft 131 having the gear 144 fastened thereto holds the rack portion 145a in engagement with the gear 144. Preferably, the rack portion 145a is defined along one side of an elongated slot 145b defined in the upper end of the reciprocating member 145.

To afford access to the chamber 91 to assemble the rack 145a with the gear 144 and to make electrical connections between the thermal responsive device 92 and the power cord 21, the rear of the post portion 80b of the handle 80 is open and adapted to be closed by a suitable closure member 150 fastened in place by a suitable screw 151 engaging a projection 82c of the handle plate 82. Preferably the closure member 150 includes a lip portion

150a which engages with the handle 80 in a manner clearly indicated in Fig. 3 of the drawings, and also includes a barrier portion 150b which extends between the terminal connectors 106a and 109 to prevent them from coming into electrical engagement. The power cord 21 enters the chamber 91 through a suitable opening 154 and the two conductors 21a and 21b thereof are electrically connected to the terminal connectors 106a and 109. In accordance with the present invention, an improved strain relief means is provided which comprises the conventional helical spring 155 disposed concentrically with the cord 21 adjacent the point where the cord enters the handle 80. The helical spring is provided with a plurality of enlarged turns 155a which are of sufficient diameter to prevent them from entering the opening 154. The helical spring is also provided at the end thereof most adjacent the opening 154 with a plurality of turns 155b of small enough diameter to enter the opening 154. These turns of reduced diameter terminate in a hooked portion 155c for a purpose which will become apparent as the following description proceeds. In accordance with the present invention, there is secured to the power cord 21 within the chamber 91 a cord clip 160 which may comprise a sheet metal stamping having a cylindrical portion 160a clamped to the cord 21 after it is inserted through the opening 154. This cord clip has a lateral projection 160b extending downwardly therefrom, as viewed in Fig. 4 of the drawings, and another T-shaped projection 160c extending upwardly therefrom. The chamber walls adjacent the opening 154 within the chamber 91 are provided with a pair of opposed recesses 161 and 162, the recess 161 being above the opening 154 as viewed in Fig. 4 of the drawings, and the recess 162 being below the opening. These recesses are clearly shown in Fig. 5 of the drawings. The hook-shaped portion 155c of the helical spring 155 is adapted to engage the T-shaped extension 160c of the cord clip 160. This is accomplished by placing the spring under tension and sort of threading it into position so that the turns of large diameter 155a are pulled against the edges of the opening 154, which opening may be tapered as is clearly shown in Fig. 4 of the drawings. Thus, the extension 160b of the cord clip is forced into the recess 162 and the T-shaped projection 160c presses against the chamber walls with the result that these projections engage the chamber walls and provide a very excellent strain relief. The inherent force of the coil spring 155 maintains the hook-shaped portion 155c in engagement with the projection 160c. At the same time the cord can readily be removed by merely rotating the cord in a clockwise direction as viewed in Fig. 5 of the drawings to unhook the hook-shaped portion 155c from the projection 160c, whereupon the spring 155 can be slipped along the cord and the cord can be removed by removing the cord clip 160.

From the above description it will be apparent that a very simple and compact iron has been provided which can be assembled in a very easy manner. The gear on the shaft 131 can be connected with the rack, and the setting of the knob 130 can readily be calibrated by releasing the nut 137 and producing relative rotation between the knob 130 and the member 136. By virtue of the thermal-responsive control device 92 being partially contained within the handle 80 and partially contained between the sole plate, it is possible to have a pressing iron with a very low silhouette and still with an open handle to permit one to insert almost the entire sole plate into the end of a sleeve, a deep ruffle or the like. The iron can be converted in a simple manner from a steam iron to a dry iron.

In view of the detailed description included above, the operation of the pressing iron of the present invention will readily be understood by those skilled in the art, and no further discussion thereof is included herewith.

While there has been illustrated and described what is at present believed to be the preferred embodiment

of the present invention, numerous changes and modifications will suggest themselves to those skilled in the art, and it is intended in the appended claims to cover all such changes and modifications as fall within the true spirit and scope of this invention.

What is claimed as new and desired to be secured by Letters Patent of the United States is:

1. A pressing iron comprising a sole plate, an electric heating element disposed in heat exchange relationship with said sole plate, a handle of somewhat L shape having one arm of the L connected to said sole plate toward the rear of said sole plate and the other arm extending forwardly over said sole plate whereby the major portion of said sole plate may be inserted into ruffles, pockets or the like without interference from said handle, means defining a chamber at least a portion of which is in said handle, thermal-responsive control means disposed in said chamber for controlling the temperature of said sole plate, manual means for selectively controlling the setting of said thermal-responsive control means comprising a knob forming an extension of said other arm and rotatable about the longitudinal axis thereof, a rotatable shaft within said other arm and extending generally along the longitudinal axis thereof, means for drivingly connecting said knob with one end of said shaft, and means for connecting the other end of said shaft with said thermal-responsive control means.

2. A pressing iron comprising a sole plate, an electric heating element disposed in heat exchange relationship with said sole plate, a molded handle of somewhat L shape having one arm of the L connected to said sole plate toward the rear of said sole plate and the other arm extending forwardly over said sole plate whereby the major portion of said sole plate may be inserted into ruffles, pockets or the like without interference from said handle, means defining a chamber at least a portion of which is in said handle, thermal-responsive control means disposed in said chamber for controlling the temperature of said sole plate, manual means for selectively controlling the setting of said thermal-responsive control means comprising a knob forming an extension of said other arm and rotatable about the longitudinal axis thereof, a rotatable shaft within said other arm and extending generally along the longitudinal axis thereof, means for drivingly connecting said knob with one end of said shaft, and means including a rack for drivingly connecting the other end of said shaft with said thermal-responsive control means.

3. A pressing iron comprising a sole plate, an electric heating element disposed in heat exchange relationship with said sole plate, a molded handle of somewhat L shape having one arm of the L connected to said sole plate toward the rear of said sole plate and the other arm extending forwardly over said sole plate whereby the major portion of said sole plate may be inserted into ruffles, pockets or the like without interference from said handle, means defining a chamber at least a portion of which is in said handle, thermal-responsive control means disposed in said chamber for controlling the temperature of said sole plate, manual means for selectively controlling the setting of said thermal-responsive control means comprising a knob forming an extension of said other arm and rotatable about the longitudinal axis thereof, a rotatable shaft within said other arm and extending generally along the longitudinal axis thereof, means for drivingly connecting said knob with one end of said shaft, a gear secured to the other end of said shaft and means comprising a rack mechanism for transmitting rotary motion of said knob to selectively control said thermal-responsive control means.

4. A steam iron comprising a sole plate, a steam generating chamber in said sole plate, means for supplying water to said steam generating chamber for conversion to steam, an electric heating element disposed in heat exchange relationship with said sole plate, a molded han-

dle of somewhat L shape having one arm of the L connected to said sole plate toward the rear of said sole plate and the other arm extending forwardly over said sole plate whereby the major portion of said sole plate may be inserted into ruffles, pockets or the like without interference from said handle, means defining a chamber at least a portion of which is in said handle, thermal-responsive control means disposed in said chamber for controlling the temperature of said sole plate, said thermal-responsive control means including a pivotally mounted cam operative selectively to control the temperature at which said thermal-responsive control means maintains said sole plate, manual means for selectively controlling the setting of said thermal-responsive control means comprising a knob forming an extension of 10 said other arm and rotatable about the longitudinal axis thereof, a rotatable shaft within said other arm and extending generally along the longitudinal axis thereof, means for drivingly connecting said knob with one end of said shaft, and means for converting rotary motion of 20 said shaft to pivotal movement of said cam.

5. In an electric iron, a sole plate having electric heating means associated therewith, a molded handle secured to said sole plate and having a chamber defined therein, said handle including means defining an opening connected to said chamber in said handle, means for supplying electrical energy to said iron comprising a power cord extending into said chamber through said opening and connected to said electric heating means, a member clamped to a portion of said cord within said chamber, a coiled spring surrounding a portion of said cord outside said handle adjacent said opening, said spring including a portion thereof extending into said opening, and means providing a strain relief device including the end of said spring inserted into said opening and cooperating means on said member engageable with the end of said spring for causing said member to bear against one of the walls of said chamber adjacent said opening thereby effectively mechanically securing said cord to said handle as far as an external tensile force on said cord is concerned.

6. In an electric iron, a sole plate having electric heating means associated therewith, a molded handle secured to said sole plate and having a chamber defined therein, said handle including means defining an opening connected to said chamber in said handle, means for supplying electrical energy to said iron comprising a power cord extending into said chamber through said opening and connected to said electric heating means, a member clamped to a portion of said cord within said chamber, a coiled spring surrounding a portion of said cord outside said handle adjacent said opening, said spring including a portion thereof extending into said opening, and means for providing a strain relief device including the end of said spring and means on said member interlocking with said end of said spring for causing said member to bear 55 against one of the walls of said chamber adjacent said opening thereby effectively mechanically securing said cord to said handle as far as an external tensile force on said cord is concerned.

7. An electric iron comprising a sole plate having electric heating means associated therewith, a molded handle secured to said sole plate and having a chamber defined therein, said handle including means defining an opening connected to said chamber in said handle, means for supplying electrical energy to said iron comprising a power 60 cord extending into said chamber through said opening and connected to said electric heating means, a member clamped to a portion of said cord within said chamber, said member having a lateral projection, a coiled spring surrounding a portion of said cord outside said handle adjacent said opening, said spring including a portion thereof extending into said opening, and means 70 for providing a strain relief device including the end of said spring inserted into said opening, said end of

16
said spring interlocking with said lateral projection for causing said member to bear against one of the walls of said chamber adjacent said opening thereby effectively mechanically securing said cord to said handle as far as an external tensile force on said cord is concerned.

8. In an electric iron, a sole plate having electric heating means associated therewith, a molded handle secured to said sole plate and having a chamber defined therein, said handle including means defining an opening connected to said chamber in said handle, means for supplying electrical energy to said iron comprising a power cord extending into said chamber through said opening and connected to said electric heating means, a member clamped to a portion of said cord within said chamber, said member including a lateral projection, a coiled spring surrounding a portion of said cord outside said handle adjacent said opening, said spring including a plurality of turns of reduced diameter capable of being inserted into said opening, means including a plurality of turns of larger diameter for limiting the maximum amount of said spring insertable into said opening, the end of said spring in said chamber terminating in a hook, and means for providing a strain relief device comprising said member and said spring with said hook interlocking with said lateral projection thereby causing a portion of said member to bear against one of the walls of said chamber adjacent said opening under the force of said spring and effectively mechanically securing said cord to said handle.

9. The arrangement of claim 8 wherein a recess is provided in the chamber wall adjacent said opening and a portion of said projection extends into said recess to prevent relative rotation between said member and the walls defining said opening.

10. The arrangement of claim 8 wherein the walls defining said opening are tapered with the opening having the smallest size at the junction point with said chamber.

11. In a steam iron, a sole plate having an ironing surface, heating means arranged in heat exchange relationship with said sole plate for heating said sole plate, a recess in said sole plate on the opposite side thereof from said ironing surface, a cover for closing said recess and defining a steam generating chamber in said iron, said cover comprising a multilayer cover including a metal foil sealing element for engaging the edges of said recess and a resilient backing member for said foil, and means for securing said cover to said sole plate.

12. A steam iron comprising a sole plate having an ironing surface, heating means arranged in heat exchange relationship with said sole plate for heating said sole plate, a recess in said sole plate on the opposite side thereof from said ironing surface, a cover for closing said recess and defining a steam generating chamber in said iron, said cover comprising a multilayer cover including a metal foil sealing element for engaging the edges of said recess, a resilient backing member engaging said foil, and a relatively rigid clamping member engaging said resilient member, said clamping member having a non-planar configuration whereby when secured to said sole plate it is forced into a planar configuration thereby to insure a good seal between said cover and the edges of said recess.

13. The steam iron of claim 12 wherein said resilient backing member is sheet asbestos and said foil is aluminum.

14. The steam iron of claim 11 including a conduit extending through said cover for supplying water to said steam generating chamber wherein said conduit holds the layers of said multilayer cover together as a unitary structure.

15. The pressing iron of claim 3 wherein said last mentioned means includes a pivotal cam member connected to said rack mechanism.

16. The steam iron of claim 11 in which said multilayer cover includes a rigid clamping member.

17. The steam iron of claim 4 wherein means are provided for impairing the heat exchange relationship between said steam generating chamber and said thermal-responsive control means.

18. A pressing iron comprising a sole plate, an electric heating element disposed in heat exchange relationship with said sole plate, a handle secured to said sole plate including a hollow somewhat horizontal portion and a hollow somewhat vertical portion, thermal-responsive means supported on said sole plate toward the rear end of said sole plate, manual selectively operable control means supported at the front of said handle, and mechanical motion transmitting means interconnecting said manual control means and said thermal-responsive means whereby selective operation of said thermal-responsive means is obtained, said motion transmitting means extending both within said hollow somewhat horizontal and said hollow somewhat vertical portions of said handle. 20

19. The pressing iron of claim 18 wherein said motion transmitting means includes a first rotatable somewhat

5

horizontal portion disposed within the somewhat horizontal portion of said handle and a second nonrotatable somewhat vertical portion disposed within the somewhat vertical portion of said handle.
